Fig. 1

Fig. 2

Fig. 3

FIG. 1 is a face view of a ceiling panel showing my new design, it being understood that the design is partially shown and continues uniformly throughout the area within the broken lines;

FIG. 2 is an enlarged fragmentary cross-sectional view taken generally along the line 2—2 of FIG. 1;

FIG. 3 is a fragmentary perspective view of the panel of FIGS. 1 and 2 showing the same face as FIG. 1, it being understood that the other panel face is flat except for the through holes shown.

I claim:

The ornamental design for a ceiling panel, as shown and described.
